UNITED STATES PATENT OFFICE.

WILLIAM H. HART, JR., DECEASED, LATE OF PHILADELPHIA, PENNSYLVANIA; BY
WILLIAM B. HART, EXECUTOR, OF PHILADELPHIA, PENNSYLVANIA.

NECKWEAR.

Application filed November 24, 1923. Serial No. 676,852.

To all whom it may concern:

Be it known that WILLIAM H. HART, Jr., deceased, late a citizen of the United States, residing in the city and county of Philadelphia, State of Pennsylvania, invented a new and useful Improvement in Neckwear, of which the following is a specification.

The invention relates to neckwear and consists of a form insertable in a bow necktie to 10 impart proper stability to the same and admit of bending of the tie whereby it may be adjusted in shape to the collar or neck of the wearer, said form being adjustable to the length of the tie whereby the form is applicable to ties of variable lengths.

The invention is satisfactorily illustrated in the accompanying drawing, but the important instrumentalities thereof may be varied, and so it is to be understood that the 20 invention is not limited to the specific details shown and described, as long as they are within the spirit or scope of the claims.

Figure 1 represents an elevation of a necktie form embodying the invention, including 25 an outline of a bow tie in dotted lines in which the form is placed and secured.

Figure 2 represents a perspective view of the form.

Figure 3 represents a longitudinal section 30 thereof on line 3—3 Figure 2.

Figures 4 and 6 represent elevations of different embodiments of the invention.

Figure 5 represents a longitudinal section on line 5—5 Figure 4.

Figure 7 represents a longitudinal section 35 on line 7—7 Figure 6.

Figure 8 represents a transverse section on line 8—8 Figure 6.

Similar numerals of reference indicate 40 corresponding parts in the figures.

Referring to the drawings.

1 and 2 designate heads opposite to each other, each being connected with the bars 3 on what may be termed the inner side of the head, the bars being adapted to be placed one on the other and slidably on each other.

In the inner side of each head is the slit 4, the slit in each head being adapted to have the bar of the opposite wing passed freely 50 through the same, thus supporting both bars and consequently slidably connecting the heads, thus producing a form for neckwear embodying my invention.

It will be seen that as the bars are freely 55 connected with the heads, the latter may be

moved to and from each other and thus the form may be lengthened or shortened and so adapted to be inserted in bows of different widths.

The material of which the form is made is 60 flat and pliable and so it will not occupy much space in the tie and may be bent in the tie by bending the latter to a desired shape relative to the collar or neck of the wearer, and so it will set properly and gracefully in position.

In Figures 4 and 5, the heads are shown as 65 slidably fitted on a single bar and so they may be moved nearer to or further from each other.

In Figures 6, 7 and 8, the bars 3 are slidably connected by the double T-piece 5 which 70 is composed of a piece of material bent on itself producing the opposite flanges 6 and the neck 7 which connects the same, said neck freely entering longitudinally extending slots 8 in the bars 3 and adapted to enter 75 similar slots 9 in the heads, it being noticed that the flanges 6 freely embrace the outer sides of the bars 3 and so hold the latter on each other but allowing them to slide on each other and so permitting the heads 1 and 2 to be adjusted to and from each other 80 according to the length of a bow.

It is evident that the heads are adapted 85 to occupy the wide side portions of the bow tie while the bars occupy the narrow central portion thereof, and so the form adds stability to the tie, permits the latter to be bent as has been stated, and when the shape of the tie has been established such shape is 90 preserved.

Having thus described the invention of 95 William H. Hart, Jr., deceased, what is claimed as new and desired to secure by Letters Patent, is:—

1. As a new article of manufacture a bow-tie form comprising a pair of spaced heads and means connecting said heads to permit longitudinal, sliding movement of at least one head toward or away from the opposite head.

2. A form of a bow tie composed of heads, and slidable bars carrying the same whereby the heads of the latter may be moved to and from each other, and the form thus adjusted relatively to bows of different lengths.

WILLIAM B. HART,
Executor of the Estate of William H. Hart,
Jr., Deceased.
